RACK FOR DIP COATING SHEETLIKE MATERIAL

Morton I. Dorfan, Pittsburgh, Pa., assignor, by
mesne assignments, to Koppers Company, Pittsburgh, Pa., a corporation of Delaware

Application June 2, 1943, Serial No. 489,349

8 Claims.

(Cl. 91—60)

The invention relates to racks for dipping sheet-like material into coating baths, and is particularly applicable to racks for dipping plain or corrugated sheet steel into baths of bituminous base coating materials according to the procedure disclosed in my copending application Serial No. 489,347, filed June 2, 1943.

The object of the invention is to provide a dipping rack for the purpose explained, on and from which sheet material may be quickly loaded and unloaded, and by which the material is held vertically in laterally spaced position for contact with a liquid coating.

The invention is illustrated in the accompanying drawings of which Fig. 1 is a side view of a partially loaded rack; Fig. 2 a plan view thereof; Fig. 3 a vertical transverse sectional view taken on the line III—III, Fig. 1; Fig. 4 a transverse sectional view of a sheet-supporting structure, the plane of view being indicated by the line IV—IV, Fig. 2; and Fig. 5 a side view of the structure shown in Fig. 4.

The rack provided according to this invention includes vertical corner posts 1 and 2 on one side and 1a and 2a on the other side, and stays connecting the upper and lower end portions of the post to form a rectangular frame. Top and bottom stays 3 and 4 connect the ends of posts 1 and 2 to each other to form one side of the frame, and top and bottom stays 3a and 4a connect the ends of posts 1a and 2a to form the other side of it. Similarly, the ends of posts 1 and 1a are connected by horizontal stays 5 and 7 to form one end of the frame, and the ends of posts 2 and 2a are connected by horizontal stays 6 and 8 to form the other end. Intermediate their ends, posts 1 and 1a as well as posts 2 and 2a are preferably connected to each other by horizontal stays 9 and 10, respectively. As shown, the several posts and stays which form a rectangular frame preferably consist of pipes connected by T's and three-way pipe fittings.

The bottom of the frame is provided with a foraminous sheet-like floor 15 which may be formed of wire mesh that rests upon the backs of angles 16 whose edges are supported by and may be welded to bottom stays 4 and 4a at the sides of the frame. By using a wire mesh floor the capillary action of the wires upon the coating material accelerates its draining from the bottoms of coated articles.

Each side of the frame is provided with a pair of vertical bars, 17 and 18 on one side and 17a and 18a on the other, which are preferably laterally adjustable for a purpose presently to be

explained. As shown in Fig. 1, these vertical bars are connected at their upper ends to T fittings 19 whose two-way portions are slidably mounted on stays 3 and 3a and their lower ends are similarly connected to supplemental stays 20 and 20a by T's 21. The several vertical bars may be held in their laterally adjusted positions by suitable set screws 22 which extend through the T fittings as shown. Extending between vertical bars 17 and 17a there are cross bars 25 and 26, and between vertical bars 18 and 18a there are cross bars 27 and 28 for engaging the edges of laterally spaced sheets 29 to hold them vertically. However, if desired, the lower cross bars 26 and 28 may be omitted.

The means formed by the cross bars for engaging the edges of the sheets preferably consist of a plurality of laterally spaced fingers which are independently movable on each cross bar into and out of engagement with the sheets adjacent to it. As shown in Figs. 4 and 5 each finger 30 may be formed of a strip of sheet metal provided at its outer edge with a notch 31 for engaging the edge of a sheet, and shaped at its other end in cylindrical form to surround a cross bar and be freely rotatable thereon. These fingers are preferably held in their laterally spaced positions by rings or collars 32 which may be borne loosely by the cross bar, or suitably connected to it. As shown in full lines in Fig. 4, finger 30 is turned downwardly to engage the edge of a sheet of corrugated steel 29, and as shown in dotted lines it is turned upwardly to release the sheet for removal from the rack. For conveniently holding the fingers in their released position, a stop bar 33 may be positioned as shown and suitably connected to the sides of the frame, and to prevent the fingers from dropping below the horizontal in their sheet-engaging position a similar stop bar 34 is arranged in the position shown and similarly connected to the sides of the frame.

As disclosed in my above-mentioned patent application, two dipping racks such as disclosed herein are suspended above a tank of coating material; in that case a bituminous base material. Each rack is suspended by a cable whose lower end is provided with four branches, one of which is connected to each of four eyes 35 that are attached to the tops of the three-way fittings at the upper ends of corner posts 1, 2, 1a and 2a. The suspension arrangement is such that while one dipping rack is in the coating tank the other is above it in a position to be unloaded and loaded, and also such that when one rack is being re-

moved from the coating tank the other is simultaneously lowered into it.

Assuming an elevated rack to be unloaded, the vertical bars 17, 17a, 18 and 18a are laterally adjusted to receive sheets 29 of a known width. This adjustment is effected by loosening set screws 22 and moving the vertical bars laterally so that they are spaced properly to receive the sheets, and are positioned equally distant from the center of the rack so that when the rack is loaded the sheets will lie centrally thereof. Fingers 30 on cross bars 25 and 26 may all be turned downwardly in a horizontal position resting on stop bar 34 as shown in Figs. 1 and 2, and the fingers 30 on cross bars 27 and 28 are swung upwardly to bear against stop 33 as shown in dotted lines in Fig. 4. The rack may be loaded from either side alone, or from both sides simultaneously. If loaded from one side only, one edge of a sheet is manually positioned in the notches of the first of horizontal fingers 30 on cross bars 25 and 26, and the sheet is moved to a position to register with the notches on the first of the fingers on cross bars 27 and 28 which are then elevated. These fingers are then manually turned downwardly to engage the edge of the thus positioned sheet. Thereafter the sheets are similarly positioned one after another in the rack until it is filled. After the rack has been lowered to dip coat the sheets, and again elevated, the sheets are removed separately from one or both sides of the rack, fingers 30 engaging one edge of each sheet being turned upwardly by hand to release the sheet. The loading and unloading may thus be quickly done, and when loaded the sheets are held vertically in laterally spaced position for proper contact with liquid coating material.

According to the provisions of the Patent Statutes, I have explained the principle and mode of operation of my invention, and have illustrated and described what I now consider to be its best embodiment. However, I desire to have it understood that, within the scope of the appended claims, the invention may be practiced otherwise than as specifically illustrated and described.

I claim:

1. A rack for dipping sheet-like material into a coating bath, comprising vertical corner posts and horizontal side and end stays connected to the upper and lower end portions of the posts to form a rectangular frame, a foraminous sheet-supporting floor at the bottom of the frame, a pair of vertical bars borne by the top and bottom of each of the opposite sides of the frame, and horizontal cross bars borne by said vertical bars and extending from one to the other side of the frame, said cross bars being provided with means for engaging the edges of laterally spaced sheets to hold them vertically.

2. A rack for dipping sheet-like material into a coating bath, comprising vertical corner posts and horizontal side and end stays connected to the upper and lower end portions of the posts to form a rectangular frame, means at the bottom of the frame for supporting the lower ends of sheets, a pair of vertical bars borne by the top and bottom of each of the opposite sides of the frame, and horizontal cross bars borne by said vertical bars and extending from one to the other side of the frame, said cross bars being provided with means for engaging the edges of laterally spaced sheets to hold them vertically, and said vertical bars being laterally adjustable.

on the frame variably to position said cross bars to receive sheets of different widths.

3. A rack for dipping sheet-like material into a coating bath, comprising vertical corner posts and horizontal side and end stays connected to the upper and lower end portions of the posts to form a rectangular frame, a foraminous sheet-supporting floor at the bottom of the frame, a pair of vertical bars borne by the top and bottom of each of the opposite sides of the frame, and horizontal cross bars borne by said vertical bars and extending from one to the other side of the frame, said cross bars being provided with a plurality of laterally spaced fingers independently movable into and out of engagement with the edges of laterally spaced sheets to hold them vertically.

4. A rack for dipping sheet-like material into a coating bath, comprising vertical corner posts and horizontal side and end stays connected to the upper and lower end portions of the posts to form a rectangular frame, a foraminous sheet-supporting floor at the bottom of the frame, a pair of vertical bars borne by the top and bottom of each of the opposite sides of the frame, and horizontal cross bars borne by said vertical bars and extending from one to the other side of the frame, said cross bars being provided with means for engaging the edges of laterally spaced sheets to hold them vertically, the sheet-engaging means on at least one of the cross bars consisting of a plurality of laterally spaced fingers independently movable into and out of engagement with the edges of the sheets.

5. A rack for dipping sheet-like material into a coating bath, comprising vertical corner posts and horizontal side and end stays connected to the upper and lower end portions of the posts to form a rectangular frame, means at the bottom of the frame for supporting the lower ends of sheets, a pair of vertical bars borne by the top and bottom of each of the opposite sides of the frame, a pair of vertically spaced horizontal cross bars borne by each pair of said vertical bars and extending from one to the other side of the frame, said cross bars being provided with means for removably engaging the edges of laterally spaced sheets to hold them vertically.

6. A rack for dipping sheet-like material into a coating bath, comprising vertical corner posts and horizontal side and end stays connected to the upper and lower end portions of the posts to form a rectangular frame, a foraminous sheet-supporting floor at the bottom of the frame, a pair of vertical bars borne by the top and bottom of each of the opposite sides of the frame, and horizontal cross bars borne by said vertical bars and extending from one to the other side of the frame, said cross bars being provided with a plurality of laterally spaced fingers independently movable into and out of engagement with the edges of laterally spaced sheets to hold them vertically, and said vertical bars being adjustable on the frame variably to position said cross bars to receive sheets of different widths.

7. A rack for dipping sheet-like material into a coating bath, comprising vertical corner posts and horizontal side and end stays connected to the upper and lower end portions of the posts to form a rectangular frame, a foraminous sheet-supporting floor at the bottom of the frame, a pair of vertical bars borne by the top and bottom of each of the opposite sides of the frame, horizontal cross bars borne by said vertical bars and extending from one to the other side of the frame to

engage the vertical edges of spaced sheets, at least one of said cross bars having rotatably mounted thereon a plurality of laterally spaced fingers independently rotatable thereon, each of said fingers being provided at its outer edge with a notch for engaging the edge of a sheet to hold it vertically, and stops for maintaining said fingers in alternate positions.

8. A rack for dipping sheet-like material into a coating bath, comprising vertical corner posts and horizontal side and end stays connected to the upper and lower end portions of the posts to

form a rectangular frame, a sheet-supporting floor at the bottom of the frame formed of wire mesh for capillary accelerating the draining of coating material from the bottoms of coated articles, a pair of vertical bars borne by the top and bottom of each of the opposite sides of the frame, and horizontal cross bars borne by said vertical bars and extending from one to the other side of the frame, said cross bars being provided with means for engaging the edges of laterally spaced sheets to hold them vertically.

MORTON I. DORFAN.
